(57) **CLAIM**

The ornamental design for a tablet computer case, as shown and described.

DESCRIPTION

FIG. 1 is a front-right perspective view of a tablet computer case, showing unclaimed corner pads, corner cut-outs, an elastic closure and cover in a completely open position; FIG. 2 is a left side elevation view of the tablet computer case of FIG. 1, showing unclaimed corner pads, elastic closure and cover in a completely open position;

FIG. 3 is a right side elevation of the tablet computer case of FIG. 1, showing unclaimed corner pads, elastic closure and cover in a completely open position;

FIG. 4 is a rear elevation view of the tablet computer case of FIG. 1, showing unclaimed corner pads, elastic closure and cover in a completely open position;

FIG. 5 is a front elevation view of the tablet computer case of FIG. 1, showing unclaimed corner pads, elastic closure and cover in a completely open position;

FIG. 6 is a top plan view of the tablet computer case of FIG. 1, showing unclaimed corner pads, corner cut-outs, elastic closure and cover in a completely open position;

FIG. 7 is the bottom plan view of the tablet computer case of FIG. 1, showing unclaimed elastic closure and cover in a completely open position;

FIG. 8 is the front right perspective view of the tablet computer case of FIG. 1, showing unclaimed elastic closure and the cover in a closed position;

FIG. 9 is the front right perspective view of the tablet computer case of FIG. 1; and,

FIG. 10 is a bottom plan view of the tablet computer case of FIG. 1.

The broken lines illustrate the environment of use only and form no part of the claimed design.
